Patented Sept. 3, 1918.

Isidore Morris Cohn INVENTOR

BY his ATTORNEY
Samuel Nehan.

UNITED STATES PATENT OFFICE.

ISIDORE MORRIS COHN, OF NEW YORK, N. Y.

TROUSERS.

1,277,866.

Specification of Letters Patent. Patented Sept. 3, 1918.

Application filed February 26, 1917. Serial No. 150,954.

To all whom it may concern:

Be it known that I, ISIDORE MORRIS COHN, a citizen of the United States, and a resident of the city of New York, in the county of Bronx and State of New York, have invented certain new and useful Improvements in Trousers, of which the following is a specification.

This invention relates in general to trousers, and in particular to the novel structure and method of finishing of the trousers top hereinafter shown and described.

In the present commonly adopted construction of the trousers top a waist band 15 is formed by sewing a piece of stiffening material, such as canvas to the inside surface of the side pieces of the trousers adjacent the upper edge thereof. A piece of lining is then sewed over the canvas, the upper portion 20 of the lining being first folded inward about a half inch to form a smooth upper edge. Stitches are usually applied at the upper end and mid-width of the lining, the latter stitches passing through the canvas 25 adjacent the lower edge thereof. The stiffening piece is thus attached to the side pieces by two lines of stitches while the top edge of the lining is attached by means of an extra line of stitches. To give a more 30 substantial waist band, the lower portion of the lining is usually also folded inward about one inch and a line of stitches applied thereto adjacent the edge of the infolded flap thus formed to keep the latter from unfolding and dropping down. The pockets 35 are usually formed of the same material as the lining and the upper portions thereof are inserted underneath the lower edge of the stiffening canvas to be there sewed together with the latter to the side pieces. The lower half of the lining of the waist 40 band is thus left hanging over the pockets and extra tacks are taken to attach this hanging portion at several points to the upper portions of the pockets.

It will thus be clear that in the present method of finishing trousers a multiplicity of distinct folding and sewing operations is required. The conditions of manufacture 45 at present are such that the finishing is not usually done at the factory where the unfinished trousers are made. More commonly, the latter are sent out to contractors who make a specialty of the finishing work. 50 This occasions an undue loss of time and extra expense for labor and material of the

waist band, all of which materially enhances the cost of production.

Furthermore, the waist band at present used, as such, hardly adds to the wearing or 60 dress qualities of the trousers. In fact, it causes the trousers top to be unnecessarily bulky and uncomfortable, especially at the pockets where there are bunched together, the canvas, the upper portion of the pockets, 65 and two thicknesses of lining, and the extra cost of production is consequently not only unwarranted, but is applied to produce an extremely undesirable structure.

My main object in this invention, therefore, is to do away with the waist band entirely and to substitute therefor a process 70 of finishing the trousers top which shall be so extremely simple that it can be done at the factory proper in very short time, at a 75 reduced cost.

Another object of my invention is to provide trousers having a simple and inexpensive waist structure.

A further object of my invention is to 80 provide trousers which shall have a neat appearance and be comfortable to the wearer.

A still further object of my invention is 85 to provide trousers which shall be cheap to manufacture.

Further objects and advantages of my invention will appear from the description and the features of novelty will be particularly pointed out in the claims.

In the accompanying drawing, Figure 1, 90 is a perspective view of the upper portion of a pair of trousers showing my novel waist construction.

Fig. 2 is a perspective view partly in section showing the construction of a side piece 95 after the first operation in my novel finishing process.

Fig. 3 is a similar view showing the side piece after the finishing by my new process is complete.

Fig. 4 is a detailed view showing my new pocket construction.

Fig. 5 is a detailed sectional view cut along line 5—5 of Fig. 4.

Referring particularly to the drawing, 10 105 are the side pieces of the trousers and 11 the waist portion which I form in the novel manner hereinafter described.

In my construction, I eliminate entirely the waist band. Instead I make the side 110 pieces somewhat longer than the required length for any given size and turn the upper

portion thereof inward forming a narrow down-turned extremity 12. Underneath this down-turned edge, I now insert a stiffening band 13 such as canvas, and then sew 5 the upper edge of the latter to the side piece by means of the line of stitches 14, as will be clear from Fig. 2. The width of the stiffening band 13 is somewhat less than that of the extended portion of the side piece. This 10 extended portion, therefore, may now be easily folded down upon the inside together with the attached stiffening piece, the extremity 12 now assuming the position 12', Fig. 3. A neat, preferably machine stitch 15 15 is now applied adjacent the lower edge of the down-turned portion, and is made to pass through the extremity 12 and the side pieces 10, as shown at 15'. The trousers top is thus finished in an easy manner in but 20 three simple operations which can easily be performed in a short time right at the factory, and with the use of no extra material.

The combined effect of this construction is to form on the top of the trousers a neat 25 cuff like portion 16 set off from the main body of the trousers by a line of demarcation made by the machine stitches 15. The usual belt straps 17 are attached preferably on the outside of the cuff portion and are made 30 preferably of a length substantially equal to the width of the cuff portion, and these thus add to the appearance of the latter and help to make it stand out more distinctly. The buttons 18 are attached preferably on the inside of the cuff portion as shown, and the trousers top is then complete.

As I have already stated, I eliminate entirely the waist lining. This not only decreases the cost of labor and material but 40 provides several additional advantages which will now be explained in detail.

In ready-to-wear trousers, it is usual to provide for an increase in girth, if necessary. This is done by folding in the side 45 pieces as at 19 and holding them together by the stitches 20. Below the said tacks, the side pieces converge to form a V 21 which may be let out for increasing the girth of the trousers by opening the tacks 22 joining 50 the back sides 23. In the ordinary form of waist structure now commonly in use the lining or a strip thereof bridges this V and before the latter may be opened to take up some of the material thereof, the lining must 55 be ripped. This is avoided in my novel construction in that I dispense with the waist lining entirely, and the V is thus always exposed and ready to be opened.

A further advantage flowing from my lining-less structure is that of a simpler, less 60 bulky and more comfortable pocket con-

struction. As will be clear from Figs. 4 and 5, the pockets 24 are provided with a tab 25 which is inserted underneath the stiffening band 13 before the final stitches 65 15 are taken. They are then attached along their width by stitches 26 to the side or back pieces and also by means of the tacks 27. This makes a very neat pocket construction, free from the multiplicity of layers of lining necessitated by the ordinary form of trousers top construction.

The fly (not shown) is of course also free from lining and adds to the simplicity of structure and to the comfort of the wearer. 75

The pattern of the pieces of the trousers is, of course, changed at the waist to provide for the extended cuff portions.

It will thus be clear that I have provided a pair of trousers which is very simple and 80 inexpensive to make, neat in appearance, and comfortable to the wearer; and that I have provided a method for finishing the trousers top which requires but very few short and simple operations, and decreases 85 the cost of production materially.

Having thus described my invention, what I claim as new and desire to secure by Letters Patent is:

1. In men's trousers a lining-less waist 90 portion formed from a continuation of the trouser top and comprising a turned down extremity integral with said continuation of the trouser top, a stiffening band stitched to the edges of said extremity, said extremity and stiffening band being infolded for a width corresponding to the width of the latter and stitches taken through said extremity and the body of the garment for securing said inturned waist portion to the 95 latter.

2. The method of finishing a pair of trousers consisting in providing the latter with an extra long body portion, turning the edge of said body portion down on the inside to 105 form a narrow turned down extremity, inserting a stiffening band within said extremity, stitching said band adjacent the upper edge thereof to said extremity, folding the body portion together with said attached stiffening band down on the inside, and stitching through the extremity of the last mentioned turned down portion thus forming the waist portion of the trousers.

Signed at New York in the county of 115 New York and State of New York this 23rd day of February, A. D. 1917.

ISIDORE MORRIS COHN.
